UNITED STATES PATENT OFFICE.

MARIAM A. BALDWIN, OF PUEBLO, COLORADO.

DOOR OR WINDOW SCREEN ATTACHMENT.

SPECIFICATION forming part of Letters Patent No. 449,514, dated March 31, 1891.

Application filed April 17, 1890. Serial No. 348,350. (No model.)

To all whom it may concern:

Be it known that I, MARIAM A. BALDWIN, of Pueblo, in the county of Pueblo and State of Colorado, have invented a new and Improved Door and Window Screen Attachment, 5 of which the following is a full, clear, and exact description.

The object of the invention is to provide a new and improved attachment specially designed for door and window screens to render the same impervious to wind, dust, and cold, and which is simple and durable in construction, cheaply manufactured, and readily applied.

15 The invention consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a front elevation of the improvement as applied to screen-doors, parts being broken out. Fig. 2 is an end elevation of the same. Fig. 3 is a like view of the same as applied in a door-casing. Fig. 4 is an enlarged sectional plan view of the improvement, the door being in position; and Fig. 5 is an enlarged sectional plan view of part of the improvement.

The improved door or window screen attachment consists, principally, of a casing A, made of a suitable fabric—such as ticking, 25 canvas, heavy sheeting, felt, &c.—sufficiently large to receive the window-screen or a screen-door B, one side of the casing being left open for the introduction of the door or screen.

On one side of the casing A are formed suitable openings C to permit the hinges D to pass through the said openings to be fastened to the door or window casing. The ends and sides of the casing A are formed into flanges E, which serve as weather-strips to fold into the door-casing F and the sill G, as is plainly illustrated in Fig. 3, so that the said flanges bend over and render the entire door or window wind and dust proof.

After the door or window is inserted in the casing A strips H, of wood or other suitable material, are placed on opposite sides of the

easing and fastened to each other by suitable bolts, nails, or other means, so as to hold the said strips firmly to the casing, at the same time pressing the sides of the casing into the wire-netting of the door or window screen, so that the sides of the casing are prevented from flapping, being securely held to the wire-netting by the said strips II.

I prefer for fastening the several strips together split nails I, as illustrated in Fig. 5, adapted to be driven through one of the strips on one side, then passing through the sides of the casing A, through the wire-netting of the door or window screen, and through the strip on the opposite side of the casing, after which the split ends are clinched, as is plainly shown in the said figure, thus securely holding the strips in place. The strips H are preferably moldings and arranged in squares or other suitable figures, the ends being jointed together in miter fashion, as is illustrated in Fig. 1.

It will be seen that when the casing is applied on a door or window screen and the door or screen is closed the flanges E render the door weather-proof. At the same time the sides of the casing prevent wind, dust, &c., from passing through the wire-netting to the inside of the house. It will further be seen that in summer time the casing can be readily removed from the screen or window, folded away until it is again desired to use the same. When the strips H are applied, as previously described, and it is desired to remove the casing, the clinched ends of the nails I are bent straight and the nails are removed, so that the strips become detached from the casing and the wire-netting.

Having thus fully described my invention, I claim as new and desire to secure by Letters Patent—

1. The combination, with a door or window screen, of a fabric casing inclosing the said screen and strips secured to the screen on opposite sides thereof and outside of the casing, substantially as and for the purpose set forth.

2. The combination, with a door or window screen, of a fabric casing inclosing the said screen and having flanges on its ends and sides, said flanges forming weather-strips, and strips secured to the opposite sides of the screen

within the frame and outside of the casing, substantially as herein shown and described.

3. The combination, with a door or window screen, of the fabric casing A, inclosing the screen and provided with flanges on its sides and ends, the strips H on opposite sides of the casing within the screen-frame, and the

split nails I for securing the strips in place, substantially as described.

MARIAM A. BALDWIN.
